UNITED STATES PATENT OFFICE.

HARRY SMITH CAMPBELL, OF DAYTON, OHIO.

CURTAIN FASTENER.

Application filed May 27, 1925. Serial No. 33,227.

This invention aims to provide a means whereby a support for a shade roller, or a support for a curtain, may be held on the top of a window frame, securely but reasonably, without resorting to the use of 5 nails, screws, or other securing elements.

It is within the province of the disclosure to improve generally and to enhance the utility of devices of that sort to which the 10 invention appertains.

Although a preferred form has been selected for illustration, it is to be understood that a mechanic, working within the scope of what is claimed, may make such changes 15 as his skill may suggest, without departing from the spirit of the invention.

In the drawings:—Figure 1 shows in elevation, the upper portion of a window frame, whereunto the device forming the 20 subject matter of this application has been applied; Figure 2 is a section on the line 2—2 of Figure 1; Figure 3 is an elevation showing, from the rear, that part of the device which is denominated the main member; Figure 4 is an elevation of the grip, together with a part of the spring arm; Figure 5 is a section on the line 5—5 of 25 Figure 4.

In carrying out the invention there is 30 provided a main member 1, in the form of a plate, comprising a body 2 having a reduced extension 3 supplied at its upper end with means for engaging the upper edge of a window frame 4, said means preferably being in the form of a depending hook 5 supplied at its lower end with teeth 6. On 35 its inner edge, the body 2 of the main member 1 is provided with a bracket 7 adapted as at 8 to hold the roller of a curtain 9, in the common and well known way. The body 2 is provided at its lower end with a short extension 10 from which a transverse seat 11 is struck. Transverse flanges 12 are struck from the body 2 of the member 1 and may be employed to retain a fixture 14 adapted to hold curtain poles, no specific 40 description of that fixture being entered into because it is one of the many stock articles wherewith the device forming the subject 45 matter of this application may be used.

A grip 15, in the form of a plate, is supplied, and is equipped at its lower end

with means for engaging the lower edge of the lintel 16 of the window frame 4, that means preferably being in the form of an 55 upstanding hook 17 terminating in teeth 18. The grip 15 has a securing means, which may be in the form of a strap 19 struck out of the grip.

The device comprises a spring arm 20, 60 shown flexed in Figure 1, the arm passing through the strap 19 of the grip 15. At one end, the arm 20 is provided with an angular finger 21 which is engaged in the seat 11 of the main member 1, the arm 65 having, at its opposite end, an angularly disposed finger 22, adapted to engage the upper edge of the lintel 16.

In operation, the hook 5 of the main member 1 cooperates with the upper edge 70 of the frame 4, the hook 17 of the grip 15 cooperating with the lower edge of the lintel 16, and the finger 22 of the arm 20 engaging the upper edge of the lintel, the arm passing through the strap 19 of the grip 15, as 75 aforesaid, and the grip being slidably adjustable on the arm to assume any position which will position the grip properly on the lintel, and give the desired curve and 80 resilient holding efficiency to the arm 20.

What is claimed is:—

1. In a device of the class described, a spring arm carrying, at its ends, members constructed to engage one edge of a window frame, one of said members having a screen support, the arm being bowed, and carrying, intermediate its ends, means for engaging the opposite edge of a window frame. 85

2. In a device of the class described, a spring arm, provided with inner and outer members constructed to engage one edge of a window frame, the outer of said members being supplied with a screen support, said members being located adjacent to the ends of the arm, and a grip constructed to engage the opposite edge of a window frame and adjustable on the intermediate portion of the arm, longitudinally of the arm, the arm being resiliently bowed. 95

In testimony that I claim the foregoing 100 as my own, I have hereto affixed my signature.

HARRY SMITH CAMPBELL.
